UNITED STATES PATENT OFFICE.

MARY W. EWING AND CHARLES B. GLOVER, OF HOUSTON, TEXAS.

STREET-SWEEPER.

1,069,608.

Specification of Letters Patent. Patented Aug. 5, 1913.

Application filed January 11, 1913. Serial No. 741,386.

To all whom it may concern:

Be it known that we, MARY W. EWING and CHARLES B. GLOVER, citizens of the United States, residing at Houston, in the county of Harris and State of Texas, have invented certain new and useful Improvements in Street-Sweepers, of which the following is a specification.

This invention relates to new and useful improvements in street-sweepers.

The object of the invention is to provide a device of the character described for the purpose of sweeping up and collecting the refuse from the surface over which the machine passes and convey the same by suction into a receptacle and further comprehends a consuming furnace in which the refuse may be consumed.

With the above and other objects in view, as will be more specifically set forth in detail hereinafter, the invention has particular relation to certain novel features of construction and operation, an example of which is given in this specification and illustrated in the accompanying drawing, wherein:

Figure 1 is a side elevation of the complete device, showing the near rear carrier wheel removed. Fig. 2 is a plan view of the complete device. Fig. 3 shows a side elevation of two of the brush sections and their connecting joints. Fig. 4 is an end view of a section of the brush, showing a portion of the end of its hood broken away. Figs. 5 and 6 show elevational side and edge views, respectively, of the brush supports, and Figs. 7 and 8 show elevational side and edge views, respectively, of the rack-and-dog arrangement, which controls the elevating windlass.

Referring now more particularly to the drawings, wherein like numerals of reference designate similar parts in each of the figures, the numeral 1 designates the frame-work of the sweeper, which is carried on front and rear carrier wheels designated, respectively, by the numerals 2 and 3. The device is provided with a motor (not shown) of the character of the ordinary automobile, which is operatively connected in the usual manner with the rear or driving wheels 3, by means of sprocket chains 4, 4, and the sprocket wheels 5, 5, the latter of which are carried by the driving wheels 3, 3, which are mounted upon the axle 6. Through the mechanism thus described the sweeper may be moved from place to place over the street or other

surface sought to be cleaned. The side members of the frame-work 1 project some distance rearwardly beyond the rear axle 6, and the rearwardly projecting portions are provided with the hinges 7, and arms 1^a are united by said hinges to said members and, consequently, may be moved up and down relative to the stationary portion of the frame-work, and fixed to said hinged portions 1^a are depending supports 8, 8, and 9, 9, whose lower ends have oblong vertically extending slots, in which are mounted sliding bearings 10 and 11, for a purpose to be hereinafter set forth.

The numerals 12 and 13, respectively, designate shafts upon which cylindrical brushes 14 and 15, respectively, are mounted. These brushes are formed in sections, and the shafts 12 and 13 have universal joints between the respective brush sections, as shown in Fig. 3, so as to make the brushes practically flexible, and the brush 14 is arranged in front of the brush 15, the sections of the former being arranged in staggered relation with respect to the sections of the latter, so that any refuse which may escape between the sections of the former will be gathered up by the latter. The brushes are formed in sections and the shafts thereof are made flexible so that said brushes will readily conform to the uneven or convex surface of the street, and all the waste and refuse matter thereon will be gathered up. The brush sections are inclosed above and in front and rear by means of inclosing hoods 16 and 17, which have inclosed ends 18 and 19, the ends being provided with bearings through which the respective shafts 12 and 13 extend, and the hoods are thus secured in fixed positions relative to the brush sections. The under sides of the hoods are open so as to expose the brushes and permit them to contact with the surface to be cleaned. Leading from the top portions of the hoods 16 and 17 are conveying pipes 20 and 21, formed of flexible material such as rubber. These conveying pipes discharge into a receiving drum 22, fixed upon the rear portion of the frame-work 1.

Mounted upon the supporting frame are two refuse receptacles 23, 23, one upon each side, and leading from the respective ends of the drum 22 are two conveyers 24, 24, which discharge, respectively, into the respective receptacles 23, 23. The conveyers 24, 24, extend some distance into the recep-

5 tacles 23, 23, and their discharge ends are curved downwardly, as shown in Fig. 1, so as to direct the refuse down toward the bottom of the receptacles. Each receptacle 23, 23 has a discharge 25, through which the refuse may be discharged into an independent conveyer, in case it is not desired to burn the same as hereinafter set forth.

10 Underneath the receptacles 23, 23, and arranged between them, is a furnace 26, into which the refuse may be discharged through the trap doors 27, 27, and wherein said refuse may be burned, the unconsumed portion falling into the ash pan 28, arranged underneath the furnace. This furnace is provided with suitable burners (not shown) such as the ordinary oil burners. Mounted upon the frame-work and in front of the respective receptacles 23, 23, are suction 15 fans 29, 29, which are driven from an independent motor 30 and communicating with the receptacles 23, 23, and with said suction fans are suction pipes 31, 31. The ends of these pipes communicating with the respective receptacles project therein and up turn so as to be out of direct alinement with the discharge ends of the conveyers 24, 24, to the end that the refuse discharged into the said receptacles will not be caught up 20 and conveyed through said pipes. It is obvious that the suction created by the fans 29, 29, will extend through the various conveyer pipes 20, 21, and 24, and will operate to suck up the refuse delivered from the brushes and discharge the same into the refuse receptacles 23, 23.

25 The rear axle 6 of the device has a centrally located rigidly mounted pulley wheel 32, and mounted in suitable bearings 33, 33, 40 carried by the arms 1^a is a transverse shaft 34, which has a centrally located, loosely mounted pulley wheel 35, which receives rotation through the belt 36 from the pulley 32. This shaft 34 has also rigidly mounted 45 sprocket wheels 37, 37, one located on each side of the pulley 35, and these wheels drive the brush 14, through sprocket chains 38, 38, which are operatively connected with corresponding sprocket wheels 39, 39, rigidly mounted 50 on the shaft 12 and between the sections thereof. Rotatably mounted in suitable bearings 40, 40, carried by the arms 1^a, is a transverse shaft 41. This shaft is driven by sprocket chains 42, 42, which are, 55 in turn, driven by the sprocket wheels 43, 43, rigidly mounted upon the shaft 34, and which drive said shaft 41 through the sprocket wheels 44, 44, rigidly mounted upon the shaft 41. The shaft 41 also carries rigidly mounted sprocket wheels 45, 45, and drive the sprocket chains 46, 46, which are, in turn, operatively connected with sprocket wheels 47, 47, rigidly mounted upon the shaft 13, between the end sections of the 60 brush 15. The shafts 12 and 13 are mount-

ed in the sliding bearings 10 and 11 of the supports 8, 8, and 9, 9, and the brushes are held yieldingly against the surface by means of strong coil springs 48, 48, and 49, 49, which are secured to the respective supports 8, 8, and 9, 9, at their respective upper ends, and whose lower ends resist against the bearings 10 and 11. The under portions of the hoods 18 and 19, immediately in front of the brushes, carry flexible aprons 50, 50, and 51, 51, whose free edges extend to the street surface, and these aprons catch up the refuse delivered from the brushes and hold it until it is caught up by the suction through the conveying tubes. A windlass 52 is provided, and attached to the extreme rear end of the frame-work 1, on each side, are strong cables 53, 53, and by means of this windlass the hinged portion of the frame-work and the brushes and their operative mechanism may be elevated, and the brushes thus lifted from contact with the surface being swept, as will be desirable when it becomes necessary to move the device from place to place. Each end of the windlass has a rigidly mounted ratchet wheel 54, 54, and pivoted to each bearing 55, 55, in which the windlass is mounted, is a dog 56, 56, which may be made to engage with the teeth of the ratchet wheels 54, 54, and the windlass secured against rotation, and the brushes thus held at any point of elevation desired. The pulley wheel 35 is arranged to be clutched with and de-clutched from its shaft 34 when desired by 50 means of clutch 57, so that the operation of the brushes may be stopped at will.

What we claim is:—

1. A device of the character described, including a frame-work, and carrier wheels 105 upon which the same is mounted, arms pivoted at one end to the frame work and extending rearwardly therefrom, a plurality of rotatable cylindrical brushes depending from and supported by said arms, said brushes being formed in sections, the sections of one brush being arranged in staggered relation to the sections of the other brush, and the sections of each brush being flexibly united together, and means for rotating said brushes.

2. A device of the character described, consisting of a suitable frame-work, carrier wheels upon which the same is mounted, a rearwardly extending arm pivoted at one 120 end to each side of the frame work, a plurality of depending supports carried by each arm, a plurality of rotatable, flexible brushes mounted in slideable bearings in said supports, resilient members holding said 125 brushes yieldingly against the surface over which they pass, inclosing hoods for said brushes, a flexible apron carried by each hood and arranged in front of its brush, a receptacle carried by the frame-work, a 130

refuse conveyer communicating with said hoods, and also with said receptacle, and conveying refuse from the former to the latter, means for creating a suction through said conveyer, and a mechanism for elevating said brushes out of contact with the surface to be swept thereby.

3. A device of the character described, including a frame work and carrier wheels upon which the same is mounted, supports flexibly united to said frame work, a plurality of rotatable cylindrical brushes depending from and supported by said supports, said brushes being formed in sections, the sections of one brush being arranged in staggered relation to the sections of the other brush and the sections of each brush being flexibly united together and means for rotating said brushes.

4. A device of the character described, consisting of a suitable frame work, carrier wheels upon which the same is mounted, an arm flexibly united at one end to each side of the frame work, a plurality of depending

supports carried by each arm, a plurality of rotatable flexible brushes mounted in suitable bearings in said supports, resilient members holding said brushes yieldingly against the surface over which they pass, inclosing hoods for said brushes, an apron carried by each hood and arranged in front of its brush, a receptacle carried by the frame work, a refuse conveyer communicating with said hood and also with said receptacle and conveying refuse from the former to the latter, means for creating a suction through said conveyer and a mechanism for elevating said brushes out of contact with the surface to be swept thereby.

In testimony whereof we have signed our names to this specification in the presence of two subscribing witnesses.
